NOVELTY SPOON

Jess L. McCain, 327 Windward Ave., Venice, Calif.

Filed May 6, 1963, Ser. No. 74,772

Term of patent 3½ years

(Cl. D54—12)

FIG. 1.

FIG. 2.

FIG. 3.

FIG. 4.

FIGURE 1 is a side view of a novelty spoon showing my new design;

FIGURE 2 is a top view thereof;

FIGURE 3 is a side elevational view of the side opposite that shown in FIG. 1; and

FIGURE 4 is an end view thereof.

I claim:

The ornamental design for a novelty spoon, substantially as shown.
